UNITED STATES PATENT OFFICE

VICTOR H. HARBERT, OF CHICAGO, ILLINOIS

BRAKE-HANGER-SUSPENDING MEANS

Application filed July 11, 1928. Serial No. 291,925.

My invention relates to means for suspending the hangers of brakes of railroad cars from the truck frames; the invention having for its object the provision of means whereby the links, whether of a continuous or U-shape form, are securely and pendently held in place against improper vibration and chatter, while at the same time permit the ready removal and substitution of either type of link without necessitating alteration in the socket or pocket portion formed integral with the truck frame.

The objects and advantages of my invention will be readily comprehended from the detailed description of the drawings, wherein—

Figure 1 is a side elevation of my improved means and portion of a truck frame provided with a pocket formed to receive the link and keeper elements.

Figure 2 is a cross sectional view taken on the line 2—2 of Figure 1 looking downwardly.

Figure 3 is a perspective view of one of a pair of complementary keeper elements, as employed in Figure 1.

Figure 4 is a top plan view illustrating a modified form of keeper elements adapted more especially for use with the U-shape type of hanger.

Figure 5 is an elevation of the construction shown in Figure 4.

Figure 6 is a vertical sectional view taken on the line 6—6 of Figure 5 looking in the direction of the arrows.

Figure 7 is a cross sectional view taken on the line 7—7 of Figure 6 looking downwardly.

Figure 8 is a perspective view of one of the keeper elements employed with the construction shown in Figure 5.

Figure 9 is a perspective view of a portion of truck frame provided with my improved integral pocket.

The exemplification of the invention as disclosed in the first three figures of the drawings is especially intended for use in connection with the continuous or closed link type of hanger, a portion whereof is shown at 15. The truck frame 16, at a point adjacent to the wheels of the truck, is preferably provided

with a projection or arm 17, the outer end whereof and on one face, namely the face disposed toward the wheels of the truck, is provided with the vertically spaced portions 18, 18 arranged to provide a socket or pocket therebetween.

The portions 18, 18 are preferably arranged at an upward inclination toward the outer ends so that the socket or pocket will decline toward the inner closed end thereof, where the two portions 18, 18 are reenforced and provided with the ribs 19 formed integral with the opposite sides of the portions 18, 18; the ribs or integral portions being provided at the forward side with an arcuate face as very

clearly shown in Figure 9. By reason of the formation of the arm with the ribs 19, 19, the pocket between the portions 18, 18, at the inner end, is provided with the socket portion 20. The lips or projections 18, 18, adjacent to their outer ends, are provided with the registering bolt-receiving openings 21, 21; and the upper projection 18 is shown reinforced by the vertically disposed rib 22 extending lengthwise of the arm 17 and preferably tapering toward the outer end of the arm, as shown in Figure 9.

Where the continuous type of link hanger 15 is to be employed, keeper elements 23, one of which is shown in Figure 3, are preferably employed. The pocket, intermediate of the projections or portions 18, 18 of the arm, are adapted to receive a pair of these keeper elements 23, which are identical in construction, with the matching or abutting faces provided with the longitudinally disposed groove 24 adapted to receive the upper end of the link 15. The longitudinal sides of the keeper elements 23, which are to be located within the pocket, are each provided with the angularly formed shoulder 25 terminating short of the ends of the keeper elements, so as to fit within the socket 20 at the inner end of the pocket between the ribs 19, 19.

The ends of the keeper elements, adjacent to the shoulder 25, are preferably formed arcuate as shown at 26, 26 so as to seat against the arcuate faces of the vertical ribs 19, 19.

It is apparent from the structure shown that with the projection or shoulder 25 on the

top and bottom keeper elements 23 seated within the socket rearward of the forward faces of the ribs 19, that longitudinal movement of the keeper elements 23 is impossible and that a proper positioning of these elements is ensured.

The projections or extensions 18, 18 of the arm 17 of the truck frame, in addition to having the outwardly upward slope as previously stated, are preferably formed to slightly diverge toward the outer ends, thereby providing a pocket of slightly greater vertical dimensions at the outer end than at the inner end thereof. The keeper elements 23 are likewise made of somewhat greater vertical dimensions or thickness at their outer sides 27, as more clearly shown in Figure 3. This causes the keeper elements to have a wedging or tight fitting relation with the arm of the truck frame and permits any possible variation to be taken up, with the result that undue vibration and chatter is eliminated.

The two keeper elements 23 are identical in construction, thus making them interchangeable and permitting either keeper element to be located either above or below the hanger, with the result that easy assembly is made possible and low cost of manufacture provided.

The forward longitudinal sides of the keeper elements 23 are each shown provided with an arcuate groove 28 disposed vertically across the front sides to receive or permit passage of a bolt 29 which is inserted through the registering holes 21 of the projections or extensions 18 of the arm; the bolt passing through the grooves 28, causing the keeper elements 23 to be held in the pocket.

By reason of this construction and arrangement, it is apparent that practically no strains are placed on the bolt 29 and that accidental displacement of the keeper elements is less likely.

In order to prevent the accidental loss of the retaining bolt 29 (a remote possibility with the construction shown), I prefer to provide the bolt locking means 30, the construction whereof is more clearly disclosed in Figure 6. This locking means consists of a bendable thin sheet metal plate having an aperture at one end for passage of the bolt 29, while the plate, after passage of the bolt 29 therethrough, is then bent upwardly and rearwardly over the head of the bolt, as shown, thus preventing accidental displacement of the bolt 29 in the event of loss of the nut on the lower end of the bolt. In order to permit the application of the bolt locking means, the upper flat face of the keeper element 23 is provided with a depression 31, see Figure 3, of a depth commensurate with the thickness of the keeper plate 30 so as to permit the keeper elements 23 to be properly

seated in the pocket between the projections 18, 18.

Where the U-shape type of hanger, indicated at 32 in Figure 5 is employed, necessitating the use of a hanger pin 33, keeper elements of the type shown at 34 in Figure 8 are preferably employed in order that the hanger pin 33, which passes through the upper eyeletted ends 35 of the hanger 32, may be properly supported and held in place against longitudinal movement, as well as proper bearing for the ends of the pin provided.

The pocket in the arm 17 of the truck frame may be identical in construction to that previously described, being formed adjacent to the inner vertical rib 19 with a groove or socket 36 to provide clearance for the enlarged eyeletted end 35 of the U-shape hanger 32 and thus permit free oscillation of the latter during the operation of the brake mechanism.

The keeper elements 34 have their main or intermediate portions formed substantially similar to the keeper elements 23 as is apparent from a comparison of Figures 3 and 8, with their matching faces each provided with the longitudinal groove 24 and their inner longitudinal sides provided with the shoulder 25 adapted to fit into the socket 20 at the inner end of the pocket between ribs 19. The keeper elements 34 at each end are provided with an extension 37 shown formed integral with what may be termed the outer longitudinal side of the keeper elements; said extension curving or extending toward the rear longitudinal side of the keeper element and in spaced relation with the main portion thereof to provide the sockets or slots 38 for reception of the upper eyeletted ends 35 of the U-shape hanger 32 and permit free oscillatory movement of the hanger 32.

The ends of the extensions 37 are enlarged as at 39 and provided on their lower or matching faces with grooves 40 aligned with the groove 24 to receive the ends of the hanger supporting pin 33; the outer faces of the enlargements of extension 37 being preferably provided with the walls 41 which close the outer ends of the grooves 40 and thus prevent longitudinal movement of the pin 33 in the composite groove 24-40.

The keepers 34 (of which a pair are employed like in the previously described construction) are identical in construction and are preferably made of gradually increasing thickness toward what may be termed the outer longitudinal sides so as to afford a wedging fit into the gradually and slightly flared pocket between the extensions 18 of the arm 17 of the truck frame.

The keeper elements 34, as shown in the drawings, are preferably of slightly greater transverse width than the keeper elements 23, for the purpose of ample strength and are therefore provided with the bolt-receiving

ing apertures 42 instead of the grooves 28 as in Figure 3, so that the retaining bolt 29 will not only pass through the apertures 21 of the extensions 18 of the arm, but will 5 also pass through the holes 42 in the two superposed keeper elements 34.

The keeper elements 34, like keeper elements 23, have been shown on their upper flat faces with a similar depression 31 for 10 the purpose of receiving the bolt-locking element 30 previously described.

In practice, where a continuous link 15 is employed, the upper end of the link is inserted into the groove 24 of the lower keeper element 23; the upper keeper element 23 is then put into position with its grooved face downwardly so that the matching grooves 24 of the two keeper elements or blocks will constitute a suitable channel 20 whereby free oscillatory movement of the hanger or link 15 will be permitted.

Where the U-shape hanger 32 is employed, the supporting pin 33 is passed through the upper eyeletted ends 35 of the hanger 32 25 and the intermediate part of the pin placed in the intermediate groove 24 of the lower keeper element, with the ends of the pin, namely the ends beyond the eyeletted ends 35 of the hanger, resting in the aligned 30 grooves 40 of the extensions 37 of the keeper element 34. The upper keeper element 34 is then put into position with its grooved face downwardly so that its grooves 24-40 may register with the grooves of the lower 25 keeper element and thus completely enclose or house the hanger supporting pin 33.

The assembled elements (either of the construction shown in Figure 1 or of the type shown in Figure 4) are then inserted into 40 the flaring and upwardly outwardly sloping pocket formed between the extensions 18, with the shoulders 25 disposed into the pocket at the inner end intermediate of the vertical ribs 19.

These shoulders not only tend to center 45 the keeper elements in proper position, but will also prevent any lateral or sidewise movement of the elements. With the keeper elements and hanger or supporting pin and hanger in place as previously described, the 50 locking bolt 29 is then inserted into place thereby maintaining the keeper elements in their wedged position in the pockets.

It is apparent from the constructions described that either type of keeper elements 55 may constitute an upper or a lower element as they are identical in construction and therefore interchangeable; and it is also apparent that substitution of either type of hanger link may be made.

It is also evident that no great strains are applied to the retaining bolt 29 and that accidental removal of the bolt, where the retaining means 30 is not employed, is also 60 less likely because of the general construc-

tion and arrangement, even though the nuts on the bolts 29 should be lost; while chatter or vibration between the elements and the truck frame is prevented and the possibility of wear thus materially reduced; while at the same time a considerable saving in material and expense is possible because of this general construction and arrangement. 70

While I believe the constructions shown and described to be the best embodiments 75 of my invention, certain modifications may be made without, however, departing from the spirit of my invention.

What I claim is:

1. Brake hanger suspending means comprising, in combination with a truck frame having a laterally disposed arm, the outer end whereof is provided with a transverse pocket gradually increasing in vertical width toward the outer end of the pocket, a pair of superposed correlated keeper plates of gradually increasing thickness toward the outer longitudinal sides and provided on their matching faces with grooves extending longitudinally of the plates adapted to register 80 and provide a link and hanger supporting pin receiving socket, and a retaining element adapted to extend vertically through the walls of the pocket in the truck frame arm. 85

2. Brake hanger suspending means comprising, in combination with a truck frame having a transversely disposed pocket open toward the truck wheels and flaring toward the outer end of the pocket, a pair of correlated keeper plates increasing in vertical 90 thickness toward the outer longitudinal sides, the matching faces of the keeper elements being each provided with a longitudinal groove adapted to provide a hanger and hanger pin receiving socket, and locking means disposed 95 downwardly through the walls of the pocket in engaging relation with said keeper plates. 100

3. Brake hanger supporting means comprising, in combination with a truck frame having a laterally disposed arm, the outer end whereof is provided with a pocket open toward the wheels of the truck, said pocket being arranged with an upward inclination and flaring toward the outer end, a pair of correlated keeper plates in superposed relation and of increasing thickness toward the outer longitudinal sides adapted to be inserted in said pocket and effect increasing 110 wedging relation as said keeper elements are moved toward the inner end of the pocket, and means for locking said plates in place. 115

4. Brake hanger suspending means comprising, in combination with a truck frame having a laterally disposed arm provided at its outer end with a pocket open toward the 120 wheels of the truck, said pocket being inclined upwardly outward and flaring toward the open end, a pair of keeper plates increasing in thickness toward the outer longitudinal sides, said keeper elements being 125 130

adapted to be superposed on each other with the brake hanger and hanger supporting pin mounted therebetween, said keeper plates being adapted to have increasing wedging relation in the pocket as said keeper plates are moved toward the inner end thereof, the outer flat faces of the keeper plates being provided with a depression, a locking bolt disposed vertically through the walls of the pocket, 10 and a bolt locking element seatable in the depression of the keeper plates and bendable across the top of said bolt.

5. Brake hanger suspending means comprising, in combination with a truck frame having a laterally disposed arm, the outer end whereof is provided with a transverse pocket closed at the inner end and at a portion of the sides, said pocket being arranged at an upward inclination toward the wheels 20 of the truck and having a slight flare toward the outer end, a pair of keeper plates adapted to be in superposed relation with each other and their matching faces grooved to provide a hanger and hanger support pin receiving socket, said keeper plates gradually increasing in vertical thickness toward the outer longitudinal sides so as to effect a wedging relation in said pocket, the inner longitudinal sides of the keeper plates being provided, intermediate of their ends, with a shoulder adapted to extend into the closed end of the pocket intermediate of the partial side walls and prevent longitudinal movement of said plates, and a locking bolt disposed vertically through the outer ends of the 35 pocket whereby displacement of said keeper plates is prevented.

VICTOR H. HARBERT.
